(57) **CLAIM**

The ornamental designs for plank support, as shown and described.

DESCRIPTION

FIG. 1 is a perspective view of plank support, illustrating an embodiment of design;

FIG. 2 is a front view thereof;

FIG. 3 is a back view thereof;

FIG. 4 is a top view thereof;

FIG. 5 is a bottom view thereof;

FIG. 6 is a right view thereof; and

FIG. 7 is a left view thereof.

FIG. 8 is a perspective view of a plank support, illustrating a second embodiment of design;

FIG. 9 is a front view thereof;

FIG. 10 is a back view thereof;

FIG. 11 is a top view thereof;

FIG. 12 is bottom view thereof;

FIG. 13 is a right view thereof; and,

FIG. 14 is a left view thereof.

The plank support is shown with a symbolic break in length. The appearance of any portion of the article between the break lines forms no part of the claimed design.

1 Claim, 6 Drawing Sheets
